UNITED STATES PATENT OFFICE

EDMUND BASIL WEDMORE, OF LONDON, ENGLAND, ASSIGNOR TO THE BRITISH ELECTRICAL AND ALLIED INDUSTRIES RESEARCH ASSOCIATION, OF LONDON, ENGLAND, A BRITISH ASSOCIATION

ELECTRIC CIRCUIT BREAKER

Application filed March 30, 1925, Serial No. 19,320, and in Great Britain April 5, 1924.

This invention consists in improvements in or relating to electric circuit-breakers and has for its object to improve the effect of such instruments under all conditions of over-load.

Generally speaking in such circuit-breakers contact is broken under oil or other fluid and hitherto it has been thought to be of advantage to utilize magnetic effects produced in the breaker during the rupture of the circuit in accelerating the rupture. In fact the modern tendency is, by various constructional features, to increase the magnetic effect or actually to produce a relatively strong magnetic field in the region of the separating contacts.

Under normal conditions the arc which is produced when the contacts are separated under oil or the like has (i. e. when the arc is short) a comparatively low resistance and this resistance increases until ultimately the circuit is broken. Particularly under extreme conditions, for example short-circuit conditions, an enforced increase in the resistance of the arc, as will occur if it is lengthened by the presence of the magnetic field, while the current value is still maintained abnormally high, will in fact, result in an increased liberation of energy within the circuit-breaker. This in many cases results in danger to life and damage to the circuit-breaker itself.

The present invention is designed to eliminate this drawback and may be stated broadly to consist in so proportioning the effective magnetic field in relation to the speed with which the contacts are separated that rupture of the circuit is obtained with, as nearly as possible, minimum liberation of energy in the circuit-breaker even under short-circuit conditions.

If the contacts are separated relatively slowly the presence of magnetic effects may comprise the equivalent of increasing the speed of separation so that the effective speed with which the circuit is broken, or in other words, the effective speed with which the length of the arc is increased may be such as to reduce the energy liberated in the circuit-breaker. It is now found, as indicated above, that if the speed is increased too much while the current value is high the arc ener-

gy is increased instead of decreased. There is therefore an optimum value for what we may term the effective speed of operation of any particular circuit-breaker in dealing with any estimated amount of energy. The effective speed must be understood to include not only the speed of separation of the contacts but the modification of that speed which is brought about by the presence of a magnetic field. Consequently also there is an optimum value of the magnetic field or effect. As the magnetic effect tends to increase proportionately with the square of the current it is obvious that very powerful effects may be obtained even on a small circuit-breaker under short-circuit conditions.

Generally speaking, therefore, I have now found that instead of the usual tendency to increase the magnetic effects in a circuit-breaker, it is of advantage to decrease these effects to such an extent that under unusually abnormal conditions, such as short-circuit conditions, the effective speed of operation of the circuit-breaker is controlled to give the most advantageous results, that is to say, to liberate as nearly as possible, the minimum energy in the circuit-breaker. The present invention may, therefore, be said to comprise in an electric circuit-breaker which would otherwise have an appreciable magnetic field associated with the arc produced during the rupture of the circuit, means for reducing the said magnetic field substantially as and for the purpose above described.

It is not practicable to estimate with great precision the maximum short-circuit current a given circuit-breaker may have to deal with and even if the device were perfectly adjusted for this particular value, it might on emergency, or due to unforeseen conditions, be called upon to deal with a larger amount of energy and owing to the way in which the magnetic effects increase a serious loss of rupturing capacity may readily follow just when it is most desirable that the circuit-breaker should operate at its best.

I find it is preferable, therefore, to depend upon speed rather than on magnetic effects for the rupturing of the circuit.

According to another aspect of the inven-

tion an electric circuit-breaker having means to determine the resultant magnetic force acting upon the arc produced at the contacts of the circuit-breaker is characterized in that 5 said means is such that the resultant magnetic force is less than it would be if no such means were provided, for the purpose of enabling, as above stated, the circuit to be ruptured with as nearly as possible a minimum 10 liberation of energy in the circuit-breaker. Preferably, said means is so designed, having regard to the speed of separation of the contacts of the circuit-breaker, that the time interval during which an arc is maintained 15 at the contacts is such that the energy released by said arc is or approaches a minimum.

According to one feature of the invention in a circuit-breaker of the type in which one 20 or more arcs tend to be deflected by proximity of other current-carrying conductors or by the proximity of magnetic material, there is provided a mass of magnetic material so arranged that its attractive effect upon the 25 arc reduces or overcomes the attractive effect of said current-carrying conductors or said first-mentioned magnetic material. Alternatively, there may be provided auxiliary current-carrying conductors, preferably connected in series in the circuit to be broken 30 by said circuit-breaker, arranged so that the forces upon said arc due to said auxiliary conductors tend to oppose those set up due to the aforesaid current-carrying conductors 35 or said first mentioned magnetic material.

For the better understanding of this invention four preferred arrangements of a circuit-breaker will now be described with reference to the accompanying drawings, in 40 which—

Figures 1 and 2 represent diagrammatically double-break circuit-breakers employing auxiliary current-carrying conductors for the purpose of this invention;

Figures 3 and 4 represent diagrammatically double-break circuit-breakers employing masses of magnetic material for the purpose of this invention, and

Figure 5 illustrates one construction of double-break circuit-breaker showing the parts drawn to scale in correct relative position, and Figures 6, 7 and 8 illustrate modified constructions to a smaller scale embodying the arrangements shown in Figures 2, 3 and 4 respectively.

Like reference numerals indicate like parts wherever applicable in each of the several figures of the drawings.

In each of the figures of the drawings, 10, 10 indicates a conductor which is to be interrupted by the circuit-breaker at two places 15 and 16. It is assumed that in each case the circuit-breaker is enclosed in an iron tank 65 containing oil so that the arcs will be at-

tracted to the iron in a direction outwards from the centre of each figure.

In the example shown in Figure 1, a loop consisting of four conductors 11, 12, 13, 14 is connected in series with the conductor 10 and is disposed in the circuit-breaker tank between the breaks 15, 16, whereat the arc occurs. The loop is arranged so that the current in the conductor 11, which is adjacent to the arc 15, is in the same direction as that through the arc 15, and similarly the current in the conductor 13 is in the same direction as that in the arc 16 which is adjacent to the conductor 13. Thus it will be seen that there will be forces tending to attract the arcs 15 and 16 towards the conductors 11 and 13, respectively. The dimensions of a circuit-breaker are so designed that this force is equal to, or is as nearly equal to as is practicable, the force due to the iron tank and other causes such as current-carrying conductors acting upon the arc. Thus it will be seen that the resultant force acting on the arc will be small or zero.

The conductor 12 is arranged parallel and adjacent to the moving contact-bar 17 of the circuit-breaker and carries a current in the same direction as the current in the moving contact-bar and thus tends to attract the latter. The purpose of this arrangement is to prevent undue acceleration of the contact-bar 17 by magnetic forces due to the other conductors or to the tank of the circuit-breaker or due to both.

In Figure 2, the loop 11, 12, 13, 14 is made integral with and connected in series with the contact-bar 17 so that, when the circuit-breaker opens, the loop 11, 12, 13, 14 travels with the contact-bar 17. It will be seen that except for this difference the arrangement shown in Figure 2 is similar to that in Figure 1. It will be appreciated, however, that there is no provision in Figure 2 for the prevention of the acceleration of the contact-bar 17.

In the arrangement shown in Figure 3, a mass of magnetic material takes the place of the conductors 11, 12, 13, 14 in Figures 1 and 2. A plate of iron 20 is supported upon an insulator 21 from the frame or casing of the circuit-breaker so that it lies close to the contact 15. A similar plate of iron 22 is supported on an insulator 23 close to the contacts 16. A third plate of iron 24 is arranged parallel to the contact-bar 17. Although these plates may be separately formed they are preferably as one piece, as shown in Figure 3. The faces of the pieces of iron 20 and 22 may, if desired, be protected by a layer of insulating material. It will be seen that if the iron casing of a circuit-breaker is close against the arc 15 or 16 it will tend to attract the arc; the pieces of iron 20 and 22 are dimensioned and adjusted so as to tend to neutralize this and other magnetic forces acting 125 130

upon the arc. The piece of iron 24 is arranged parallel to the contact-bar 17 so that it tends to attract the bar 17 thereby to prevent undue acceleration of this part due to other stray magnetic forces.

In Figure 4 the mass of iron is itself carried upon the contact-bar. Two iron plates 20 and 22 are supported by insulators 21 and 23 upon the contact-bar 17 so that they are opposite and adjacent to the contacts 15 and 16 respectively. The arrangement of the plates 20 and 22 is similar to that described with reference to Figure 3, but the plate 24 is omitted. By suitable design and arrangement of the plates 20 and 22 the magnetic forces upon the arcs 15 and 16 may be minimized, but with this construction there is no means of preventing or minimizing the magnetic acceleration of the contact-bar 17.

In Figure 5, a construction of circuit-breaker is illustrated in detail. The main lead conductor 10 passes through an insulator 30 to the conductors 11, 12 and 13, whereof the conductors 11 and 13 are preferably each encased in an insulating sleeve, as illustrated. The conductor 13 passes through another insulator 31 and is electrically connected by a conductor indicated diagrammatically at 14, which is in the plane of the insulator tops, and passes through an insulator 32 to the main contacts 15 of usual or well-known construction. The contacts 15 are provided with auxiliary or spark contacts 33 as well understood; and on the other side of the break, main contacts 16 are shown with their auxiliary or spark contacts 34. The cross-bar 17 is mechanically connected to the movable ones of the contacts 15 and 16, and the fixed contact 16 is electrically connected through an insulator 35 to the other main lead 10. A shield 46 of insulating material is provided between the insulators 31 and 35 to prevent any accidental bridging of the contacts carried by these insulators.

The conductor 12 is formed with a collar 36 which fits loosely over an insulated switch-rod 37 fixed to the cross-bar 17. Between a fixed collar 38 on the switch-rod 37 and a boss 39 on the underside of the tank-cover 40 is a spring 41 which constitutes the usual opening or driving spring for forcing the cross-bar 17 downwardly when the switch contacts are to be opened. The main and auxiliary contacts, the conductors 11, 12 and 13, and cross-bar 17, are enclosed in the usual oil-containing tank 44, preferably provided in the usual manner with a lining 42 enclosed by the cover 40. The normal oil level is indicated at 43 and the position of the center-line of the cross-bar 17, when the switch is fully open, is indicated at 45.

A constructor of a circuit-breaker according to this invention will be able, by well-known methods, to calculate the electromagnetic forces which, without the presence

of the conductors 11, 12 and 13, would arise in the circuit-breaker. Equally, also, by well-known methods, he can calculate the necessary positions of the conductors 11, 12 and 13 in relation to the other parts of the circuit-breaker to obtain the required neutralizing effect so as to leave the spring 41 as substantially the sole means to control the speed of separation of the electrodes.

Figures 6, 7 and 8 are similar to Figure 5 but embody the diagrams shown respectively in Figures 2, 3 and 4. Thus in Figure 6 the conductors 13 and 11 are carried by insulators 47 on the cross-bar. The moving contacts are mounted on insulators 48 on the cross-bar 80 and are connected to the conductors 13 and 11 by means of the conductors 17 and 12.

In Figures 7 and 8 the arrangements are substantially as described in connection with Figures 3 and 4, a mass of magnetic material 20, 22, 24 being mounted on fixed insulators 21 and 23 in Figure 7, while in Figure 8 magnetic masses 20, 22 are mounted on the cross-bar 17 through insulators 21, 23.

It is evident that although in the above description it has been stated that the conductors 11, 12, 13, 14 and the pieces of iron 20 and 22 are designed and disposed so as to minimize the magnetic forces acting upon the arcs, it is not essential that this should be the case, for the design may be such that the forces acting on the arcs may be reduced to any required extent.

It will be appreciated that the above description is given by way of example only and that many modifications may be made without departing from the scope of this invention.

I claim:

1. An electric circuit breaker in which there is a single series circuit having conductors and a breaking point, a conductor portion adjacent such point, and a further conductor portion adjacent a part of the circuit that moves in the breaking operation of the breaker, said conductor portions being so arranged that the current flowing in them at any instant produces electromagnetic effects tending respectively to prevent deflection of the arc formed at the breaking point and to prevent undue acceleration of the said moving part brought about by interaction between said moving part and adjacent parts of the breaker caused by the electromagnetic effects set up by the current flowing in the said moving part.

2. An electric circuit breaker comprising a pair of contacts, a contact bar normally bridging such contacts and movable in a direction substantially perpendicular to its length in the breaking of the circuit, a current-carrying conductor disposed adjacent said bar and arranged so that electromagnetic forces due to the current flowing therein exert an effect upon said bar tending to

- oppose other electromagnetic forces present in the breaker which would otherwise accelerate unduly the speed of the circuit breaking movement of said bar.
3. An electric circuit breaker comprising a current-carrying conductor arranged in series in the circuit to be broken, a pair of contacts, a contact bar normally bridging such contacts and movable in the breaking 70 of the circuit in a direction substantially perpendicular to its length and away from said conductor, said conductor being so arranged in relation to said bar that, at any instant, current flowing in the same direction in both 75 these parts sets up electromagnetic forces which tend to oppose other electromagnetic forces present in the breaker which would otherwise accelerate unduly the speed of the circuit breaking movement of said bar.
4. A circuit breaker having a pair of co-operating contacts which are bridged by an arc on breaking circuit, which arc will be urged away from the shortest path between the contacts by electromagnetic forces due 80 to adjacent parts of the breaker, and means to produce other electromagnetic forces opposing the aforesaid forces to retain the arc substantially in the shortest path between the contacts.
5. A circuit breaker having a pair of co-operating contacts which are bridged by an arc on breaking circuit, which arc will be urged away from the shortest path between the contacts by electromagnetic forces due to 85 adjacent parts of the breaker, and a conductor carrying current and situated so as to produce other electromagnetic forces opposing the aforesaid forces to retain the arc substantially in the shortest path between the contacts.
6. A circuit breaker having a pair of co-operating contacts which are bridged by an arc on breaking circuit, which arc will be urged away from the shortest path between the contacts by electromagnetic forces due to adjacent parts of the breaker and a conductor connected in series with the contacts and situated so as to produce other electromagnetic forces opposing the aforesaid forces to retain the arc substantially in the shortest path between the contacts.
7. A circuit breaker having a pair of co-operating contacts which are bridged by an arc on breaking circuit, which arc will be urged away from the shortest path between the contacts by electromagnetic forces due to adjacent parts of the breaker and a body of magnetic material situated so as to produce other electromagnetic forces opposing the aforesaid forces to retain the arc substantially in the shortest path between the contacts.
8. A circuit breaker having two fixed and two moving contacts in series whereof the 120 conducting leads to the fixed contacts ex- 125 tend substantially parallel to one another, whereby an arc formed between the co-operating contacts will be urged away from the shortest path between the contacts by electromagnetic forces and a conductor carrying a current and situated between the pairs of contacts so as to have a portion lying substantially parallel to the line joining each pair of separating contacts with the current flowing in the same direction, so as to produce other electromagnetic forces opposing the aforesaid forces to control the position of the arc.
9. A circuit breaker having two fixed and two moving contacts in series whereof the 130 conducting leads to the fixed contacts extend substantially parallel to one another whereby an arc formed between the co-operating contacts will be urged away from the shortest path between the contacts by electromagnetic forces and conductors connected in series with the contacts so as to have a portion lying substantially parallel to the line joining each pair of separating contacts with the current flowing in the same direction, so as to produce other electromagnetic forces opposing the aforesaid forces to control the position of the arc.
10. A circuit breaker having two fixed and two moving contacts whereof the conducting 135 leads to the fixed contacts extend substantially parallel to one another whereby an arc formed between the co-operating contacts will be urged away from the shortest path between the contacts by electromagnetic forces and a body of magnetic material situated between the pairs of contacts so as to produce other electromagnetic forces opposing the aforesaid forces to control the position of the arc.
11. A circuit breaker having a fixed contact and a moving contact, a moving conductor associated with the moving contact and situated so that when a current flows in it electromagnetic forces due to other parts of the breaker act on it tending to accelerate or retard its movement, and means for producing other electromagnetic forces opposing the aforesaid forces so that the rate of movement of said conductor is substantially independent of the current flowing in it.
12. A circuit breaker having a fixed contact and a moving contact which are bridged by an arc on breaking circuit which arc will be urged away from the shortest path between the contacts by electromagnetic forces due to adjacent parts of the breaker, a moving conductor associated with the moving contact and situated so that when a current flows in it electromagnetic forces due to other parts of the breaker act on it tending to accelerate or retard its movement and means for producing other electromagnetic forces opposing the aforesaid forces so that the rate of elongation of the arc depends substan-

- tially only on the operating mechanism and is substantially independent of the current flowing in the arc.
13. A circuit breaker having two fixed and two moving contacts, a moving conductor connected between the moving contacts so as to move in a direction substantially perpendicular to its length, conducting leads extending from the fixed contacts substantially parallel to one another in the direction in which the moving contacts move to make circuit, and means to produce electromagnetic forces tending to retard the opening movement of the moving contacts.
14. A circuit breaker having two fixed and two moving contacts, a moving conductor connected between the moving contacts so as to move in a direction substantially perpendicular to its length, conducting leads extending from the fixed contacts substantially parallel to one another in the direction in which the moving contacts move to make circuit, and a fixed conductor connected in series with the contacts and situated parallel with the moving conductor so that the currents in the two conductors are in the same direction and so that the moving conductor recedes from the fixed conductor on breaking circuit.
15. A circuit breaker having two fixed and two moving contacts, a moving conductor connected between the moving contacts so as to move in a direction substantially perpendicular to its length, conducting leads extending from the fixed contacts substantially parallel to one another in the direction in which the moving contacts move to make circuit, and a body of magnetic material situated adjacent to the moving conductor so that the latter recedes from it on breaking circuit.
16. A circuit breaker having two fixed and two moving contacts, a moving conductor connected between the moving contacts so as to move in a direction substantially perpendicular to the line joining said contacts, conducting leads extending from the fixed contacts substantially parallel to one another in the direction in which the moving contacts move to make circuit, wherein the moving conductor is formed with a loop having one side situated between the conducting leads to the fixed contacts in which side the current travels in a direction opposite to that in which it would travel if the conductor were straight.
17. A circuit breaker having a pair of cooperating contacts which are bridged by an arc on breaking circuit, a container of magnetic material having a wall adjacent the arc whereby magnetic forces are set up urging the arc away from the shortest path between the contacts, and means to produce other electromagnetic forces opposing the aforesaid forces to retain the arc substantially in the shortest path between the contacts.
18. A circuit breaker having two fixed and two moving contacts in series whereof the conducting leads to the fixed contacts extend substantially parallel to one another, an enclosing case of magnetic material having a wall situated adjacent a point of separation of said contacts whereby an arc formed between the cooperating contacts will be urged away from the shortest path between the contacts by electromagnetic forces and means for producing other electromagnetic forces opposing the aforesaid forces so as to control the position of the arc.
19. A circuit breaker having a fixed contact and a moving contact, a moving conductor associated with the moving contact, an enclosing case of magnetic material having a wall situated adjacent said moving conductor so that the latter approaches and recedes from it so that when a current flows in said conductor electromagnetic forces act on it tending to accelerate or retard its movement and means for producing other electromagnetic forces opposing the aforesaid forces so that the rate of movement of said conductor is substantially independent of the current flowing in it.
20. A circuit breaker having two fixed and two moving contacts, a moving conductor connected between the moving contacts so as to move in a direction substantially perpendicular to its length, a case of magnetic material having a wall situated adjacent said moving conductor so that the latter approaches and recedes from it in operation and means to produce electromagnetic forces tending to urge said moving conductor away from said magnetic wall.
